UNITED STATES PATENT OFFICE.

CLINT MADARIS, OF CHATTANOOGA, TENNESSEE, ASSIGNOR TO SCOTT & WILLIAMS,
INCORPORATED, OF NEW YORK, N. Y., A CORPORATION OF MASSACHUSETTS.

SAFETY DEVICE FOR KNITTING MACHINES.

Application filed November 30, 1926. Serial No. 151,746.

My invention relates to circular knitting machines having cylinders and dials each carrying knitting elements in cooperative relation, in which it is possible to lift the dial 5 out of working position when desired. One of the objects of my invention is to provide means which will stop the machine if the gears driving the dial are not put back properly meshed after the dial has been lifted out 10 of its working position. Another object of my invention is to provide means which operates promptly if the operator fails to mesh the dial and needle cylinder in proper peripheral relation, whether that error is 15 great or small.

In the accompanying drawings,

Fig. 1 is a front elevation of the upper portion of a circular knitting machine showing the needle cylinder, the dial and its operating mechanism and the stop motion tripped;

Fig. 2 is a plan view of the mechanism shown in Fig. 1, with the stop motion set;

Fig. 3 is an elevation taken on the line 25 3—3 of Fig. 2 showing the connections of the new stop motion;

Fig. 4 is an enlarged detail of Fig. 3 showing the pin and notch on the dial driving gears; and

Fig. 5 is a vertical section on the line 5—5 of Fig. 4 taken at right angles to that figure.

The invention will be shown and described embodied in the well known Scott & Williams type of seamless hosiery machine, but it should be understood that this invention is applicable to any circular knitting machine having two carriers each with knitting elements therein.

In the drawings, the rotating needle cylinder 40 260 is mounted in the bedplate B and surrounded by the usual stationary cam ring 271. The dial D is shown mounted in a latchring 550 pivoted on a bracket 401 at the back of the machine in such manner that it 45 may be swung upwardly out of operative relation with the cylinder. This lifting of the dial is necessary to permit access to the fabric or to the interior of the cylinder or to the needles. The dial and cylinder are driven 50 at the same peripheral speed by connecting gearing from the main drive shaft 32, the main bevel gear 31 driving the needle cylinder. The gearing to the dial D comprises a dial drive bevel gear g^6 on the main drive

shaft 32, and a pinion g^5 meshing therewith on a vertical shaft 13, the movement of this latter shaft being transmitted to the dial D through the horizontal drive shaft 14 and the vertical dial spindle d . The dial drive shaft 13 is mounted in a bearing 12 on the bedplate B and the horizontal drive shaft 14 is mounted in a dial bracket 15 on the latchring, which bracket also supports the dial spindle d . On the upper end of the vertical shaft 13 is a bevel gear g^4 adapted to drive a bevel gear g^8 on the adjacent end of the horizontal shaft 14. The motion of this latter shaft is transmitted to the dial spindle d by bevel gears g^1 , g^2 . The gears g^1 , g^2 , g^3 and g^4 can be protected by a cover 16 if desired, which has a spring snap 558 fastening it to the bracket 12 to hold the gears g^3 , g^4 in proper operating position.

It will be observed that the dial is disconnected from the main drive shaft 32 when the latch ring is raised, by the gears g^3 and g^4 becoming unmeshed. This gives opportunity for the dial and cylinder to get out of their proper peripheral relation and if the machine were run with the two gears g^3 , g^4 improperly meshed the knitting elements would strike together and be broken. In practice it is found that these gears frequently are not properly engaged after the dial has been raised. According to the present invention means have been devised for stopping the driving pulley of the machine promptly if the operator attempts to run the machine when the gears g^3 , g^4 are not properly meshed. The stop motion proper can be of any well-known type such for instance as a stop finger 335 pivoted under the table C of the machine adapted to be thrown into engagement with the stop ring 334 of the pulley 47, all as shown and described in the Robert W. Scott Patent Number 1,270,063 dated June 18, 1918. The stop finger is controlled by an actuating lever 336 on top of the table C held under the tension of a spring 337 against a notch in the trip finger 338 as usual. This stop motion is tripped by means on the gearing driving the dial, when the dial and cylinder are not in time. I prefer to associate these means with the gears g^3 , g^4 . These means include a notched surface 339 associated with the gear g^4 and a pin 340 on the gear g^3 adapted to ride on the notched surface. I prefer to

make the notched surface in the form of a horizontal notched ring adjustably fastened to the gear g^4 , and the pin 340 is held vertically in a slot in the back face of the gear 5 g^3 by a strap 343. This pin is normally pressed downwardly against the notched surface 339 by a spring 342 acting through a lever 341 pivotally mounted in a slot extending longitudinally in the hub of the gear g^3 . 10 When the pin 340 rests in the notch in the surface 339 the lever 341 does not protrude from the hub of the gear g^3 , and the two gears are in the proper angular relation to each other. If the vertical shaft 13 and the 15 horizontal shaft 14 revolve at the same speed as the dial spindle it will be physically impossible for the dial and cylinder to be out of time if the pin 340 is in the notch in the surface 339. If the gearing is such that the 20 vertical shaft 13 and the horizontal shaft 14 each revolve at least twice as fast as the dial and cylinder, then it is possible for the pin to be in its notch when the dial and cylinder are 180° out of time. Such a remote possibility can be avoided by looking at the 25 markings on the dial and cylinder when replacing the dial.

The lever 341 in the hub of the gear g^3 is adapted to trip the stop motion, acting 30 through a rod r^1 mounted on a shaft passing through a bracket r^2 on the dial drive shaft bearing 12 and a hinged rod r^3 connecting to the trip finger 338.

The upper end of the rod r^1 is curved in 35 such manner and is so positioned with relation to the hub of the gear g^3 that when the pin 340 rests on the flat part of the surface 339 rather than entering the notch and is thereby forced upwardly, this curved end of 40 the lever r^1 is tipped downwardly by the end of the lever 341 away from the pin no matter in which direction the gear g^3 is revolving. This tipping of the lever r^1 will cause the trip finger 338, the actuating lever 336, and 45 the stop finger 335 to swing in the directions indicated by the arrows in Fig. 2, thus causing the main drive shaft to be stopped.

This stopping device will be found to be 50 simple, practical and also prompt in its action. Variations of the structure described will readily occur to those skilled in the art without departing from the scope of my invention.

I claim:

1. A circular knitting machine having two 55 carriers each carrying knitting elements and gearing for driving one carrier capable of being disconnected, in combination with means adapted to stop the machine when said gearing is not properly connected. 60

2. A circular knitting machine having a needle cylinder and a dial each carrying knitting elements, gearing for driving the dial, and a hinged portion adapted to swing the dial into and out of working position 65 with the cylinder and simultaneously to engage and disengage the gearing driving the dial, in combination with a stop motion and means adapted to operate said stop motion when the gearing is not correctly engaged. 70

3. A circular knitting machine having a needle cylinder and a dial, knitting elements in said cylinder and dial, and connecting means for driving said cylinder and dial including two gears adapted to be meshed and unmeshed, in combination with a stop motion and means associated with said two gears adapted to operate said stop motion when the gears are not properly meshed. 75

4. A circular knitting machine having a revolving needle cylinder and a revolving dial, knitting elements in said cylinder and dial, and means for driving said cylinder and dial synchronously, in combination with a stop motion and a notched surface and pin means revolving with the means driving the dial adapted to operate said stop motion when said pin does not mesh properly with said notched surface. 80

5. A circular knitting machine having a 85 revolving needle cylinder and a revolving dial, knitting elements in said cylinder and dial, a pivoted latch ring carrying said dial, and connecting gearing for driving said cylinder and dial including two gears adapted to be meshed and unmeshed when said latch ring is lowered and raised, and a stop motion, in combination with a notched ring revolving with one of said two gears, and a pin and lever revolving with the other of said gears, adapted, when said gears are not meshed properly, to trip said stop motion. 90

In testimony whereof I have signed my name to this specification.

CLINT MADARIS.
